(57) **CLAIM**

The ornamental design for a beverage container, as shown and described.

DESCRIPTION

FIG. 1 is a front elevational view of a beverage container showing my new design;

FIG. 2 is a perspective view thereof;

FIG. 3 is another perspective view thereof;

FIG. 4 is a top plan view thereof; and,

FIG. 5 is a bottom plan view thereof.

The portions of the beverage container shown in broken lines form no part of the claimed design.
